John P. Nolan

UNITED STATES PATENT OFFICE.

CHARLES F. AMES, OF BROOKLYN, NEW YORK, ASSIGNOR OF ONE-FIFTH TO ALPHONSE H. E. BERCHEM AND ONE-FIFTH TO HARRY S. SCHANCK, BOTH OF NEW YORK, N. Y.

CENTRIFUGAL PUMP.

Application filed October 22, 1925. Serial No. 64,085.

This invention relates to centrifugal pumps; my object being to provide a pump of simple and efficient construction and operation wherein a plurality of independently acting impellers of the same or varied diameter are operatively mounted within separate volute chambers arranged in a unitary housing or casing. The improved pump is primarily designed for use in connection with the vacuum producing apparatus for steam heating systems disclosed in my co-pending application Serial No. 64,086, filed October 22, 1925, but it is to be understood that the pump may be efficiently used in conjunction with apparatus for handling liquids of the same or variable pressure and capacity, as for example, with water purification systems or the foamite system.

In the drawings—

20 Figure 1 is a horizontal section, partly in elevation, of a twin pump embodying a preferred form of my invention.

Fig. 2 is a transverse vertical section of the pump, as on the line 2—2 of Fig. 1.

25 Fig. 3 is a front elevation of the pump, with the ported head removed.

Fig. 4 is an elevation of said head.

Fig. 5 is a section, as on the line 5—5 of Fig. 2.

30 Fig. 6 is a sectional detail of one of the rotors or impellers, and its adjuncts.

Referring to the drawings, 11, 12 designate complementary lower and upper sections constituting a pump housing or casing, with 35 in which are formed in spaced relation to each other two volute chambers 13, 14 having independent outlets 15, 16, respectively.

Extending centrally through the volute chambers is a power driven shaft 17 on 40 which are mounted to rotate within the respective chambers 13, 14 two impellers 18, 19 of the single suction or the double suction type. These impellers may be of the same or different diameters, depending upon 45 the particular service to be performed by the pump. In the present instance impellers of the single suction type and of different diameters are illustrated, such impellers being arranged face to face with their central 50 eyes in register with adjacent inlet ports 20, 21 from supply conduits 22, 23, respectively, which are formed in the casing so as to occupy the space between the walls of the two chambers. The outlets 15, 16 and supply 55 conduits 22, 23 extend through a flanged

portion on the lower section 11, and to which flanged portion a suitable coupling head may be bolted, as herein described. If desired the impellers instead of being arranged face to face may be arranged back to back.

60 In one aspect of my invention the inlet conduits between the volute chambers may be connected respectively with the separating chamber and the overflow or condensate chamber of a vacuum producing apparatus

65 for steam heating systems, as described in my co-pending application aforesaid, in which connection the impellers are of different capacities to meet the relative requirements of volume and pressure; one (16) of

70 the outlets being in communication with an ejector which leads to the separating chamber and is in operative connection with the return line from the heating system, and the other outlet (15) being in communication

75 with a boiler feed-water pipe. In another aspect of my invention, wherein the pump is employed as, for example, a two stage pump, the outlet (15) of one chamber is connected with the inlet conduit (23) of the

80 other chamber in such a way that a series operation is performed and the liquid by the respective pump elements, that is to say, when liquid is supplied to and is discharged from one volute chamber by the comple-

85 mental impeller such liquid is delivered to the supply inlet of the other volute chamber and therein further acted upon by the impeller of the latter preparatory to the final discharge of the liquid. To this end,

90 the inlet and outlet conduits to and from the respective chambers communicate with a ported head or manifold 24 of suitable character which is appropriately bolted to the flanged portion lower section of the housing.

95 This head preferably comprises a body having therein an intake port 25 leading from a suitable source of liquid supply through pipe 30 to the inlet conduit 22; a diagonal or cross-over passage 26 connect-

100 ing the outlet 15 with the inlet 23, and a port 27 in registry with the outlet 16. The latter port is in communication with a pipe 28 leading to a suitable point of discharge.

105 By the construction described it will be seen that the pump elements are arranged in close relation and are directly connected for series operation in such a manner that an easy and short flow travel of the liquid or

110 liquids from one element to the other is ef-

fected. It will also be seen that by the chambers therein in spaced relation, central duplex suction and discharge connections inlet ports for said chambers, outlets from said chambers, impellers mounted in said chambers on a common axis of rotation and having their eyes in register with said ports, and supply conduits arranged between and leading respectively to the said inlet ports, said supply conduits and outlets opening through the casing adjacent to each other and adapted to have a coupling head se- 50
5 capacities. If the apparatus be used in connection with the foamite system the manifold 24 will be omitted, in which case the liquids would be handled separately and finally mix at the end of the discharge line.
10 The manifold 24 is also omitted when the pump is used in connection with a steam heating-system.

In the particular construction herein illustrated the hubs of the impellers are 15 mounted in floating casing rings 29 which serve to prevent leakage of the liquid around the suction portions of the impellers, and the shaft 17 upon which the impellers are mounted is supported by bearing brackets 20 31 which are cast integral with the lower section of the housing. This shaft is protected from the action of the liquid by means of spaced sleeve sections 32 which, encasing the shaft, are firmly pressed against the impellers by means of external lock nuts 33 located 25 beyond the glands 34 of the stuffing boxes 35. The bracket at the outboard end of the pump is provided with a combined radial and adjustable thrust bearing 36, and the 30 bracket at the inboard end is provided with a radial bearing 37 only; these bearings being designed for grease lubrication.

My invention is not limited to the particular structural details herein disclosed, as the 35 construction may be modified within the principle of the invention and the scope of the appended claims.

I claim—

1. A centrifugal pump comprising a two- 40 part casing having a plurality of volute

chambers therein in spaced relation, central duplex suction and discharge connections inlet ports for said chambers, outlets from said chambers, impellers mounted in said chambers on a common axis of rotation and having their eyes in register with said ports, and supply conduits arranged between and leading respectively to the said inlet ports, said supply conduits and outlets opening through the casing adjacent to each other and adapted to have a coupling head se- 50
45

2. A centrifugal pump comprising a casing having a plurality of volute chambers therein in spaced relation, central inlet ports for said chambers, outlets from said chambers, impellers rotatably mounted in said chambers and having their eyes in register with said ports, supply conduits arranged between and leading respectively to the said inlet ports, and a head secured to the casing 60 having a cross-over connection between the outlet of one chamber and the supply conduit of another chamber, an inlet port and an outlet port communicating with the other supply conduit and the other outlet. 65

3. A centrifugal pump comprising a casing having a plurality of volute chambers therein in spaced relation, outlets for said chambers, impellers rotatably mounted in said chambers, inlet conduits in said casing 70 arranged between and leading respectively to the impellers, and a head secured to said casing and having a cross-over passage between the outlet of one chamber and the inlet of another chamber and also separate 75 ports for the other outlet and inlet conduit.

Signed at the city of New York, in the county and State of New York, this 7th day of October A. D. 1925.

CHARLES F. AMES.
